UNITED STATES PATENT OFFICE.

LUIGI SCANFERLA, OF MILAN, ITALY.
FUSE-SETTING DEVICE FOR PROJECTILES.

1,246,331.

Specification of Letters Patent. Patented Nov. 13, 1917.

Application filed March 4, 1914. Serial No. 822,537.

To all whom it may concern:

Be it known that I, LUIGI SCANFERLA, a subject of the King of Italy, residing at 20 Via Gustavo Modena, Milan, in the Kingdom of Italy, have invented certain new and useful Improvements in Fuse-Setting Devices for Projectiles, of which the following is a specification.

The fuse setting device which forms the object of the present invention permits of adjusting shrapnel fuses with the necessary quickness and exactitude for quick firing, no matter what position the movable ring of the fuse assumes; during the setting the projectile remains immovable. It is not necessary that the axis of the setting device should occupy a vertical or approximately vertical position, but it may assume the position which is most convenient to the gunner.

According to the present invention, when for various reasons the setting of the fuse does not take place regularly, the gunner is notified of the delayed functioning of the device thereby avoiding the defect of firing off timed shrapnel with the fuse wrongly set.

A slight diminution of the size of the novel adjusting device also renders it practicable to construct a hand setting device which is manipulated in a manner similar to the fixed setting and which gives the same results.

For the operation of the novel setting device, it is only necessary to form recesses in the outer surface of the body of the fuse and of the movable ring, these recesses being similar to those with which the 75 mm. shrapnel of the Italian type and of the 40 Krupp type are provided, or to provide collars and projections both of which permit of the action of the seizing devices.

An embodiment of the invention is illustrated by way of example in the accompanying drawing, in which:—

Figure 1 is a longitudinal section of the setting device with the projectile inserted therein.

Fig. 2 shows the same in external elevation.

Fig. 3 represents the block of the hook support partly in elevation and partly in section.

Fig. 4 shows the outer sleeve partly in elevation and partly in section.

Fig. 5 represents the small block of the

lever support partly in elevation and partly in section.

Fig. 6 shows the setting device viewed from the front with the end plate partly removed.

Fig. 7 represents the clamping device for holding the projectile.

Figs. 8 to 15 illustrate a modified construction of the apparatus.

Fig. 8 is a longitudinal section of the modified form of a setting device with inclined axis.

Fig. 9 shows the same in external elevation combined with the setting device carrier which forms a part of the caisson,

Fig. 10 illustrates the separate arrangement of the seizing member of the movable fuse ring.

Fig. 11 is a section on the line *f—g* of Fig. 10.

Figs. 12, 13 and 14 represent respectively, sections on the lines *a—b*, *d—c* and *m—n* of Fig. 8.

Fig. 15 is a section on the line *r—s* of the assembling device of the apparatus with the adjusting device carrier fixed on the bush (See Fig. 9.)

Figs. 16 to 18 illustrate an apparatus of the same type with vertical axis.

Fig. 16 is a longitudinal section thereof.

Fig. 17 is a front elevation, and

Fig. 18 illustrates a portion of the device for retaining the projectile in the setting device.

The novel setting device consists of a body 1 (Fig. 1) in the form of a tube which contains and supports the several elements; in so far as the setting of the device and of the fuse are concerned, it is composed broadly of a block 2 and of a smaller block 3 which are rotatable on the axis of the adjusting device and which are independent of or connected with each other according to the moment of adjustment.

The block 2 or hook support block (Fig. 3) is provided with a hook 4 (Figs. 1, 3, and 12) which is bill-shaped and which is rotatable about the bolt 7 and under the influence of a small spring 43 (Fig. 12), engages in the recess 5 provided in the body of the fuse 6.

The block 2 contains a small block 3 (Fig. 1) termed the block of the lever support (Fig. 5) because it is provided with a lever 8 which rotates upon a pivot 9 supported by two lugs. The shorter lever arm 10 enters

a cavity provided in the block 3 and its end comes into contact with the movable ring 11 of the fuse (Fig. 1) into the recess 12 of which it enters by the action of the spring 13, when, upon the rotation of the block 3, the recess 12 and the said arm 10 register. A carrying yoke 14 (Fig. 5) projects from the block 3 and carries a handle 15; a recess is arranged in the carrying yoke in which 10 the lever arm 16 of the lever 8 moves freely, and, as will hereinafter appear, this arm has an important function to fulfil.

The devices for the adjustment of the instrument according to the variations of temperature and other circumstances are controlled by the tangential screw 19 and scale 20, the devices for adjusting the instrument according to the firing ranges are controlled by screw 23 and scale 24; said devices form 15 a part of the block 2 of the hook support and consist of a ring 17 fixed on the block and along an arc of approximately 90° on the outer surface of this ring worm wheel teeth 18 for a tangential screw 19 (Fig. 6) are 20 formed while along another arc of approximately 90° a scale 20 is cut for adjusting the fuse; they also comprise a ring 21 (Fig. 1) which is recessed in a suitable manner and is rotatable on the block 2; throughout 25 the entire extent of its outer surface, it is provided with worm wheel teeth 22 for another tangential screw 23 (Fig. 6) and in addition to the worm wheel teeth with a scale 24 for the firing ranges. On its edge 30 this ring 21 is provided with a tooth 25 (Fig. 6). A bush 26 (Figs. 1 and 4) which is rotatable about the block 2 and locked thereto by means of screw 19, covers the worm teeth 18 and 22 and supports the tangential screws 35 19 and 23 (Fig. 6); upon the same bush, an index 27 with double arrows is marked one of them forming an index for the scale 24 on the ring 21 and the other forming an index for the adjusting scale 20 on the ring 40 21 which scale is partially uncovered by a slot.

The firing data relating to the setting of the fuse, to the aiming and to the range are recorded on the setting device by manipulating 45 the wheel 28 of the tangential screw 23 for the range.

By acting upon one or the other of the tangential screws, the tooth 25 on the ring 21 is caused to approach or recede from the 50 bill of the lever 4, thereby causing the recesses 5 and 12, respectively, to be a greater or less distance apart in the final adjustment of the fuse, depending upon the adjustment given the screws 19 or 23.

60 The two adjustments are independent of each other and can be effected no matter whether the projectile is in the setting device or not.

When the projectile is introduced into the 65 setting device, the gunner acts upon the

handle 29 of the clamping device 30 (Figs. 1, 2 and 7) which serves for retaining the projectile. The clamping device is not absolutely necessary especially when the hand setting device is used, as the action of the gunner's hands is sufficient for holding the projectile.

When the projectile has been introduced into the setting device, the gunner by means of the handle 15 is able to rotate the block 75 of the lever support in the direction indicated by the arrows on the bush (Fig. 2).

The end of the arm 10 of the lever 8, which slides on the movable ring 11 of the fuse comes into contact with the recess 12 at a certain point, enters this recess under the action of the spring 13 and from this moment causes the ring 11 to rotate together with the block 3. Simultaneously the other lever arm 16 springs out to such a position 80 that owing to the continuance of the rotation of the block, it encounters the tooth 25 on the ring 21 (Fig. 6) which engagement could not take place previously. This engagement, produces the rotation of the block 90 2 and the two blocks 2 and 3 rotate together until the bill of the hook 4 brings all the moving parts to rest by engaging in the recess 5 of the fuse body. At this point the ring 21 has been rotated a given arc, depending upon the prior position of recess 5 of stationary ring 6.

The fuse has then been adjusted in accordance with the firing data.

If for any reason the projectile should 100 not have entered the setting device completely, that is to say not to such an extent that the recesses in the fuse occupy the correct position relatively to the engaging members, or if the movable ring of the fuse, owing 105 to its being too readily displaceable, is caused to participate in the rotary movement of the block 3, before the end of the lever arm 10 registers with the recess in the ring, the fuse cannot be set because the contact of the end of the arm 16 of the lever 8 with the tooth 25 does not take place. As the devices in movement are not brought to rest, the gunner's attention is drawn to the 110 fact that the fuse has not been set or has been 115 badly set.

Another constructional form of the setting device is illustrated in Figs. 8 to 15 in which the elements corresponding to those described in connection with the first constructional form are designated by the same reference numerals.

This modified form of adjusting device consists of a body 1 (Fig. 8) which receives the projectile and supports the several devices; the carrier 32 is combined with this body its end being given a cup formation 33, 34 with the object of enabling the apparatus to be readily and speedily connected with the block 35, 36 of the adjusting device car- 120 125 130

rier 37. The carrier 32 carries the members for firmly retaining the projectile in the adjusting device; these members consist of a dog 38 rotatable on the bolt 39 and of a handle 40 with a cam 42 rotatable on the bolt 41. The body 1 supports the block 2 which is rotatable on the shaft of the setting device.

The block 2 supports the several devices for adjusting the instrument and for setting the fuse, which are:—

A plate 3 (Figs. 8 and 12) which rotates upon the block by means of the tangential screw 19 and which carries the hook 4, the bill 4' of this hook engaging the recess 5 in the body of the fuse under the pressure of the spring 43. Upon the outer surface of the plate and on the opposite side of the worm threaded portion thereof the adjusting scale 20 (Fig. 9) is engraved, a portion of it being visible through a slot.

A ring 22 (Figs. 8 and 16) is rotatable in the block by means of a tangential screw 23; upon the outer surface of the ring, the hectometer or other range scale is engraved, a portion 24 of this scale being visible through another slot in the wall of the block 2 (Fig. 9); upon the inner surface of the ring a tooth or projection 25 is provided (Figs. 8 and 13).

A small bowl-shaped block 44 (Figs. 8 and 13) is also rotatable upon the shaft of the setting device by means of the external handle 15 with which it is provided. The small block 44 also carries the lever 8 movable on the bolt 9 (Figs. 8, 10 and 11).

The end 10 (Figs. 8, 10 and 11) of the short lever arm 8 is hooked and forms the seizing member of the movable fuse ring. The long arm 16 of the lever 8 is formed as a ring (Figs. 8 and 13) and ends in a tooth 16.

In order to adjust the projectile after it has been introduced into the setting device and the lever 40 has been applied, the gunner adjusts the screw 23 (Fig. 13) for the range and the screw 19 for the aiming, whereby the registration of the arrow index with the desired adjustments (which are independent of each other and therefore separately variable) are obtained.

The gunner then acts upon the handle 15 in such a manner that the fuse is screwed onto the apparatus. This produces the rotation of the small block 44 and immediately thereafter of the block 2 until all the devices in movement are brought to rest by the hook 4 engaging the recess 5. The fuse is then set and the projectile is withdrawn after it has been freed by acting on the dog 38.

The devices referred to are brought to rest in the following manner.

During the rotation of the small block 44 the end 10 of the short arm of the lever 8 slides on the movable ring of the fuse until

it encounters the groove 12 into which it sinks under the action of the spring 48; this linear displacement of the end 10 produces a magnified displacement of the long arm 16 of the same lever 8 whose tooth 16', which is located adjacent the projection 25 on the ring 22, engages therein. From this moment the block 2 is caused to participate in the rotation of the small block 44 until the bill 4' of the hook 4 brings all the moving devices to rest by entering the recess 5 in the body of the fuse.

When, for any reason the hook 4 has become fast in the recess 5 before the tooth 16' encounters the projection 25 the parts 80 are brought to rest by this latter contact.

If for any reason, such as incomplete insertion of the projectile, defective friction of the movable ring and so forth, one of the two driving members should not act, the 85 parts in question will be brought to rest and the gunner, after at most a second revolution of the handle, (which takes place idly) is notified of the fact that the fuse has not been set.

The apparatus described can be fixed to guns with vertical axis, for which apparatus it is only necessary to modify the form of the fitting for the carrier of the setting device and the arrangement of the adjusting scales in order to facilitate their reading.

Figs. 16, 17 and 18 illustrate an embodiment of the invention meeting these requirements.

By means of a member 33, the setting 100 device is supported on the carrier 32. The centering socket 45 is fixed on the carrier and serves as a bolt for the small block 44 and for the block 2 which are rotatable upon a common axis, the axis of the setting device. Two bevel pinions 50 and 51 serve for the transmission of the rotary movement. A ring of steel balls arranged between the socket and the small block, reduces the friction between the contacting surfaces. The 110 weight of the projectile is supported almost entirely by the centering socket.

In the example here illustrated, the body 1 of the setting device is rotatable in the block 2 and is mounted with a special gripping device 52 for fixing the projectile during setting.

What I claim and desire to secure by Letters Patent of the United States is:—

1. A fuse adjusting mechanism, comprising two normally independently rotatable members, one of said members carrying a fuse-engaging element and the other of said members carrying a fuse ring engaging element, and co-operating means between the 120 two members to cause both to rotate in unison when one of said members has been turned in a given direction to a predetermined point relatively to the other member and rotation thereof is continued in the same 130

direction beyond the predetermined point until the fuse engaging element engages the said fuse.

2. A fuse adjusting mechanism, comprising two normally independently rotatable members, one of said members carrying a fuse engaging element and the other of said members carrying a fuse ring engaging element, coöperating means between the two members to cause both to rotate in unison when one of said members has been turned in a given direction to a predetermined point relatively to the other member and rotation thereof is continued in the same direction beyond the predetermined point until the fuse engaging element engages the said fuse, and means carried by one of said members to so adjust said coöperating means that the ring and fuse will be adjusted to the desired relative position.

3. A fuse adjusting mechanism comprising two rotatable members, means carried by one of said members to lockingly engage the fuse at a given point in its rotation, and means carried by the other member to lockingly engage the fuse ring and simultaneously engage the member provided with the fuse-locking means to cause both members and the fuse ring to rotate together until brought to rest by the fuse-locking means coming into play.

4. A fuse-adjusting mechanism comprising two rotatable members, means for primarily rotating one of said members, means carried by the other member to lockingly engage the fuse at a given point, and means carried by the primarily rotated member to lockingly engage the fuse ring and when so engaged to make engagement with the member provided with the fuse-locking means only to cause the two members and the fuse ring to rotate together until brought to rest by the fuse-locking means engaging the said given point of the fuse.

45 5. A fuse adjusting mechanism, comprising a shell receiving body, means for

clamping the shell to the body, two members independently rotatable upon the said body, means carried by one of the members to lockingly engage the fuse, and means carried by the other member to lockingly engage the fuse ring and when so engaged to cause both members and the fuse ring to rotate together until brought to rest by the fuse locking means engaging the fuse.

6. A fuse adjusting mechanism, two rotatable members, fuse engaging means carried by one of the said members, a bush member, a ring member, means mounted upon the bush member and coöperating with the ring member and with the member provided with the fuse locking means for relatively adjusting each independently of the other, and fuse ring engaging means carried by the remaining rotatable member and adapted to engage the ring member to cause the fuse ring and said two rotatable members to turn together until brought to rest by the fuse locking means engaging the fuse.

7. A fuse adjusting mechanism, comprising a body, shell clamping means carried by the body, fuse and fuse ring members rotatably mounted upon the body, fuse locking means carried by the rotatable fuse member, a bush member, means between the bush member and the rotatable fuse member for relatively adjusting the said members, a ring, adjusting means between the bush member and the said ring, and locking means mounted upon the rotatable fuse ring member to engage the fuse ring and be engaged by the above-mentioned ring and cause all the parts to rotate together until brought to rest by the fuse locking means engaging the fuse.

In testimony whereof I affix my signature in presence of two witnesses.
